UNITED STATES PATENT OFFICE.

ERNEST CAMP AND ALBERT F. SCHATZEL, OF SAN DIEGO, CALIFORNIA.

EAR PROTECTOR.

Application filed June 7, 1920, Serial No. 387,005. Renewed November 15, 1922. Serial No. 601,165.

To all whom it may concern:

Be it known that we, ERNEST CAMP and ALBERT F. SCHATZEL, citizens of the United States, residing at San Diego, in the county 5 of San Diego and State of California, have invented certain new and useful Improvements in Ear Protectors, of which the following is a specification, reference being had to the accompanying drawings.

10 This invention relates to ear protectors, and more particularly to a protecting device for the ear adapted for use by persons engaged in occupations where the ears are subjected to the action of the wind.

15 An important object of our invention is to provide a device of the above character which may be readily and quickly applied and which is neat in appearance.

20 A further object of the invention is to provide a device of the above mentioned character, which, when subjected to the wind will have a tendency to cling more closely to the ear and protect the same.

25 Other objects and advantages of the invention will become apparent throughout the course of the following description.

30 In the accompanying drawings, wherein for the purpose of illustration is a shown a preferred embodiment of our invention, and wherein like reference characters designate like parts throughout:

Figure 1 is a perspective view of our ear protector, and

35 Figure 2 is a sectional view taken there-through.

Referring now more particularly to the drawings, the numeral 10 indicates our ear protector as a whole, the protector preferably being formed of a sheet of transparent 40 material, such as celluloid, or the like.

The protector embodies a body portion 11 which is adapted to cover the funnel of the ear. This body portion is provided upon its forward face with an angular extension 12 which is adapted to contact with the side of the face between the ear and the cheek bone and which is adapted to fit tightly against the face at the point of junction. The body portion 10 is provided at the 45 upper portion thereof with a vertical extension which is adapted to be bent back upon itself to form a hooked portion 13

adapted to engage against the rear face of the funnel of the ear at the upper portion thereof and adjacent the junction of the ear with the head. The body portion is likewise provided, at its lower end, with a longitudinal extension 15, adapted to be bent back upon itself and serving in the completed device as a hook for engaging the lobe 60 of the ear and retaining the bottom portion of the body portion in position.

It has been found in actual practice that a device of this character when applied to the ear will not be affected by the action of the wind other than such action causing the body portion 10 to grip against the ear more firmly, the forward extension 12 effectually preventing the wind from passing under the forward edge of the body portion 70 and raising the same from the ear.

It will be obvious that while we have shown and described our ear protector as provided with attaching means formed integrally therewith, any suitable attaching 75 means may be employed in securing the same to the ear, the unitary construction merely being employed for the purpose of reducing the cost of manufacture.

Having now described our invention, 80 what we claim is:

1. In an ear protector, a substantially flat plate fitting against the outer side of the ear of the wearer provided with integral hook shaped extensions adapted to engage the ear 85 of the wearer and likewise provided with an integral extension adapted to lie against the cheek of the wearer.

2. In an ear protector, a substantially flat plate fitting against the outer side of the ear of the wearer provided upon the upper portion thereof with an integral hook shaped extension adapted to engage the upper portion of the funnel of the ear adjacent its juncture with the head and upon 95 its lower with a second hook shaped extension adapted to similarly engage the lobe of the ear, and likewise provided with an angularly disposed integral extension adapted to lie against the cheek of the wearer. 100

In testimony whereof we hereunto affix our signatures.

ERNEST CAMP.
ALBERT F. SCHATZEL.
